AIR CONDITIONER FRONT PANEL

Harold N. Minick, Marshall, Mich., assignor to McGraw-
Edison Company, Milwaukee, Wis., a corporation of
Delaware

Filed Jan. 2, 1964, Ser. No. 78,017

Term of patent 14 years

(Cl. D62—4)

Fig. 2

Fig. 3

Fig. 4

Fig. 7

FIG. 1 is a front elevation view of the air conditioner front embodying my new design;

FIG. 2 is a left side elevation thereof as shown in FIG. 1;

FIG. 3 is a right side elevation thereof as seen in FIG. 1;

FIG. 4 is a section view along line 4—4 of FIG. 1, partially broken away;

FIG. 5 is a top view of the air conditioner front of FIG. 1;

FIG. 6 is a bottom view thereof; and

FIG. 7 is a section view along line 7—7 of FIG. 1.

The lining shown on the panel face surface portions is intended to indicate contrast.

I claim:

The ornamental design for an air conditioner front panel, substantially as shown.
